CLAIM

The ornamental design for a faucet, as shown and described.

DESCRIPTION

FIG. 1 is a perspective view taken from the top, front and left side of a faucet showing my new design; FIG. 2 is a left side elevational view thereof, the right side being a mirror image of the left side; FIG. 3 is a top plan view thereof; FIG. 4 is a front elevational view thereof; FIG. 5 is a rear elevational view thereof; and, FIG. 6 is a bottom plan view thereof.

Fig. 1.Fig. 4.Fig. 2.Fig. 3.Fig. 5.
